Patented Apr. 15, 1919.

UNITED STATES PATENT OFFICE.

GEORGE F. BRIGDEN, OF WALTHAM, MASSACHUSETTS.

INDICATOR.

1,300,339.

Specification of Letters Patent. Patented Apr. 15, 1919.

Application filed January 11, 1919. Serial No. 270,624.

To all whom it may concern:

Be it known that I, GEORGE F. BRIGDEN, a citizen of the United States, residing at Waltham, in the county of Middlesex and State of Massachusetts, have invented new and useful Improvements in Indicators, of which the following is a specification.

This invention relates to indicators such as so-called "kitchen reminders" adapted to remind a housewife of articles to be ordered from tradesmen.

The object of the invention is to provide a simple, durable and convenient indicator which may be produced at such small cost as to warrant the free distribution of indicators embodying the invention for advertising purposes, and having such desirable qualities that the recipient is liable to retain and use the indicator.

The invention is embodied in the improvements which I will now proceed to describe and claim.

Of the accompanying drawings forming a part of this specification,—

Figure 1 is a front side view of an indicator embodying the invention.

Fig. 2 is an edge view of the same.

Fig. 3 is a front side view of a portion of the indicator body.

Fig. 4 is a section on line 4—4 of Fig. 1.

Fig. 5 is a rear side view of a portion of the indicator.

Fig. 6 is a section on line 6—6 of Fig. 5.

The same reference characters indicate the same parts in all of the figures.

In the drawings, 12 represents a body of sheet material such as cardboard, or thin sheet metal, in one or more edges of which are formed slots 13 extending through and inwardly from the edge, the outer ends of the slots being open, as shown by Fig. 3.

On the body at the inner ends of the slots are printed the names of various articles as shown by Fig. 1. In the slots are inserted 5 slides, each including a neck portion 14, movable in a slot, and end portions 15 bearing on opposite sides of the body.

After the insertion of the slides a sheet metal reinforcing strip 16 is applied to the margin of the body, said strip being channeled or U-shaped in cross section, and its sides being pressed closely against the marginal portions of the body sides. The chief function of the strip 16 is to close the open 5 ends of the slots and confine the slides therein. Another function is to stiffen the slotted

edges of the body and prevent the displacement or bending of the portions of the edges between the slots.

The body and reinforcing strip may be 60 bent by any suitable means or in any suitable manner along the lines α , α (Fig. 1), to incline the slotted portions outwardly from the back side of the body, as shown by Fig. 2, and thus clear the inner enlargements 65 15 of the slides from a wall, or other support on which the indicator is mounted. The reinforcing strip has another function, in that it retains the form thus imparted to the body, the strip being of sheet metal, and, 70 therefore, adapted to make the bent form permanent. Still another function of the reinforcing strip is to protect and retain in place the outer portions of the calendar disks 18 which are pivoted at 19 to the body 12, 75 and are inscribed, the one with the names of the calendar months, and the other with numerals indicating the days of a month. The disks are located behind the body, and portions of their outer sides are visible 80 through openings 20, in the body, so that elements of a perpetual calendar are provided. One side of the reinforcing strip is provided with slots 21, through which portions of the disks project. The portions of the strip at the inner edges of the slots are offset and form guards 22 which prevent the projecting portions of the disks from being bent backwardly from the body 12. 90

Advertising matter may be printed on the outer side of the body, and a match receptacle 23 may be attached to the body.

The user of the indicator may move the slides toward the inner ends of the slots, to 95 indicate that articles named at said inner ends are wanted.

I claim:

1. An indicator of the character stated, comprising a body of sheet material having 100 open-ended slots extending through and inwardly from one or more of its edges, slides including neck portions movable in said slots and enlarged end portions bearing on opposite sides of the body, said neck portions being insertible in the open ends of the slots, and a channeled marginal reinforcing strip clamped upon and covering the edges of the strip to prevent displacement of the strip edges between the slots, and close the 110 outer ends of the slots.

2. An indicator of the character stated,

comprising a body of sheet material having open-ended slots extending through and inwardly from one or more of its edges, slides including neck portions movable in 5 said slots, and enlarged end portions bearing on opposite sides of the body, said neck portions being insertible in the open ends of the slots, and a channeled marginal reinforcing strip clamped upon and covering 10 the edges of the strip to prevent displacement of the strip edges between the slots, and close the outer ends of the slots, the reinforcing strip and body being flexible, and the slot-containing portions of the body 15 and the portions of the reinforcing strip thereon being inclined outwardly from the back side of the body.

3. An indicator of the character stated, comprising a body of sheet material having

open-ended slots extending through and inwardly from one or more of its edges, slides including neck portions movable in said 20 slots, and enlarged end portions bearing on opposite sides of the body, said neck portions being insertible in the open ends of the 25 slots, a channeled marginal reinforcing strip clamped upon and covering the edges of the strip to prevent displacement of the strip edges between the slots, and close the outer ends of the slots, the strip at one edge of the 30 body being provided with slots and with offset disk-confining portions at the inner edges of the slots, to confine portions of calendar disks pivoted to the body.

In testimony whereof I have affixed my 35 signature.

GEORGE F. BRIGDEN.
